FIG. 1

FIG. 2

FIG. 3

FIG. 1 is a front view of a pair of sunglasses showing our new design;

FIG. 2 is a side view of said pair of sunglasses taken from the right side thereof as viewed in FIG. 1, the side not shown being of substantially the same appearance as the side shown; and

FIG. 3 is a top view thereof.

The temples are shown broken away in FIG. 3 for convenience of illustration.

The dominant features of our design reside in those portions shown in full lines.

We claim:

The ornamental design for a pair of sunglasses, substantially as shown and described.
